UNITED STATES PATENT OFFICE.

GEORGE W. WHITEMAN, OF PHILADELPHIA, PENNSYLVANIA.

INSULATED RAIL-JOINT.

1,349,352.

Specification of Letters Patent. Patented Aug. 10, 1920.

Application filed May 27, 1920. Serial No. 384,555.

To all whom it may concern:

Be it known that I, GEORGE W. WHITEMAN, a citizen of the United States, and a resident of Philadelphia, Pennsylvania, have invented certain new and useful Improvements in Insulated Rail-Joints, of which the following is a specification.

In all insulated rail joints, a sheet of insulation is interposed between the meeting ends of the rails. Under normal conditions, the rail ends are subject to separation due to climatic changes with the result that this sheet of insulation gets loose, is battered by the traffic passing over the joint when in the loose condition and is frequently damaged to such an extent as to render the joint substantially useless for the purpose desired. Additionally, separation of the rail ends subjects them to such severe hammer blows by the traffic as to result in the rail-heads breaking at the joint in many instances.

One object of my invention is to provide means whereby the meeting ends of the rails are held in close engagement with the plate of insulation interposed between the same, thereby insuring that it will maintain its position under all conditions and also avoiding all danger of battering the same out of shape.

A further object of my invention is to provide means, properly insulated, for bringing the rail ends in close engagement with the plate of insulation interposed between the same.

These and other features of my invention are more fully described hereinafter, reference being had to the accompanying drawings, in which:

Figure 1, is a side elevation of one form of insulated rail joint having the features comprising the subject of my invention.

Fig. 2, is a sectional plan view of the joint, taken on the line 2—2, Fig. 1.

Fig. 3, is a modified construction of insulated joint within the scope of my invention.

Figs. 4 and 5, are cross sectional views taken on the line 4—4 and 5—5, Fig. 2, and

Fig. 6, is a cross sectional view on the line 6—6, Fig. 3.

In the drawing 1, 1, represent the meeting ends of a pair of rails between which is placed a sheet of insulated material 2; the latter having a contour the same as the cross sectional contour of the rails.

In the present instance, my improvements are shown in connection with a particular

form of insulated rail joint in which a flanged chair or rail seat 3 receives the meeting ends of the rails 1, 1; the joint including wooden blocks 4 and 5 disposed on opposite sides of the rail ends, with an L-shaped section of insulating material 6 lying between the chair 3, the rail ends and one of the wooden joint members. In such form of joint, the retaining bolts 8, which are provided with proper insulation are passed through the chair, wood blocks and rails, and are secured by suitable nuts 9, which may be disposed on the chair side of the joint.

To hold the rail ends in close engagement with the interposed sheet 2 of insulating material, I provide positive retaining means which may also be employed to bring the rail ends together. For this purpose, I may provide the rails with angle brackets 11, which may be bolted thereto as indicated at 12, and provided with suitable insulating plates 13; which brackets are connected together by a longitudinal tension bolt 14, threaded at each end as at 14^a and properly insulated from the brackets; suitable collars 15, of insulating material being provided. The threaded ends 14^a of the bolt 14 pass through laterally disposed ears 11^a of the brackets, and the rail ends may be drawn together, prior to tightening the nuts 9, on the bolts 8, by tightening nuts 16 applied to the threaded ends 14^a of the tension bolt 14. By this means, the rail ends of the insulated joint are kept in close contact with the interposed insulating plate 2. The holes in the rail ends for the passage of the bolts 8 are more or less elongated to permit the rails to be drawn together without affecting the position of the bolts with respect to the members of the joint.

In Figs. 3 and 6, I have shown a modified arrangement in which a joint, having the usual form of splice-bars indicated at 17, is provided with a pair of connecting members 18; such members being secured at one end to the rails by bolts 19, and having at their opposite ends laterally projecting ears 18^a through which a short bolt 19^a may be passed, with nuts 20 at each end of the bolt 19^a to draw the members 18 together and with them the rail ends to which these connecting members are attached by the bolts 19. In this form of joint, plates 21 of insulating material are interposed between the splice-bars and the rail ends, and plates 22

- of insulating material are placed between one of said splice-bars and the connecting members 18. The bolts 8^a connecting the rail ends and the splice-bars may be provided with insulating sleeves 23. It may be desirable, in some instances, to elongate the holes provided in the connecting members 18 for the passage of the bolts 8^a, as indicated at 24.
- 10 As the insulated joints are only placed at intervals of one to ten or twenty of the ordinary joints, there is ample provision for normal expansion or contraction of the rails at these other joints.
- 15 I claim:
1. The combination, with a pair of rails, of a sheet of insulating material interposed between the meeting ends of said rails, and insulated means for holding said rail ends together and maintaining them in contact with said interposed sheet of insulating material.
  2. The combination, with a pair of rails, of a sheet of insulating material interposed between the meeting ends of the same, and means insulated from said rails for holding their ends in permanent contact with said interposed sheet of insulating material.
  3. The combination, with a pair of rails, of a sheet of insulating material interposed between the meeting ends of the same, means for holding said rail ends in permanent contact with said interposed sheet of insulating material, and means for insulating said holding means from the rails.
  4. The combination, in an insulated rail joint, of a pair of rail ends, securing means for said rail ends, a sheet of insulating material interposed between the meeting ends of the rails, means for drawing the rail ends together for permanent contact with said sheet of insulating material; said means including brackets carried by the rails adjacent to the ends of the same, and means for insulating said brackets from the means for drawing the rail ends together.
  5. The combination in an insulated rail joint, of a pair of rail ends, securing means for said rail ends, a sheet of insulating material interposed between the meeting ends of the rails, insulating material disposed between said rail ends and the securing means,

a tension bolt for drawing the rail ends together for permanent contact with said sheet of insulating material, brackets carried by the rails adjacent to the ends of the same to which said tension bolt is connected, and means for insulating said brackets from said tension bolt.

6. The combination of a pair of meeting rail ends, a sheet of insulating material interposed between the ends of the same, insulated means for holding said rail ends together, a connecting member having apertures for the passage of the rail-end-securing means, brackets carried by the rail ends; said connecting member having threaded ends adapted to pass through ears carried by said brackets, means for securing said threaded ends to the brackets and for imparting longitudinal movement to the connecting member whereby the rail ends may be drawn into engagement with the interposed sheet of insulating material.

7. The combination, of a pair of meeting rail ends, a sheet of insulating material interposed between the ends of the same, insulated means including bolts for holding said rail ends together, a longitudinal connecting member having apertures for the passage of said bolts, brackets carried by the rail ends having apertured ears, said connecting member having threaded ends adapted to pass through said ears, and insulating means for securing the threaded ends of said connecting member to the brackets and for imparting longitudinal movement to the same whereby the rail ends may be drawn into engagement with the interposed sheet of insulating material; said contact being effected before the joint securing bolts are tightened.

8. The combination, with a pair of rails, of a sheet of insulating material interposed between the meeting ends of the same, means insulated from the rails for holding their meeting ends in permanent contact with said sheet of insulating material, and means for preventing lateral displacement of said sheet of insulating material.

In witness whereof I have signed this specification.

GEORGE W. WHITEMAN.
